G. L. DU LANAY.

Harvester Cutter.

No. 91,102.

Patented June 8, 1869.

Joseph Leas
Ellis Abrams

G. L. Du Laney

UNITED STATES PATENT OFFICE.

G. L. DU LANEY, OF MECHANICSBURG, PENNSYLVANIA.

IMPROVEMENT IN HARVESTER-CUTTERS.

Specification forming part of Letters Patent No. **91,102**, dated June 8, 1869.

To all whom it may concern:

Be it known that I, G. L. DU LANEY, of Mechanicsburg, in the county of Cumberland and State of Pennsylvania, have invented new and useful Improvements in Harvester-Cutters; and I do hereby declare that the following is a full and exact description thereof, reference being had to the accompanying drawings, and to the letters of reference marked thereon.

Figure 1 is a perspective view of the sickle-bar, showing the cutter-blades in position. Fig. 2 is an end view of the sickle-bar, showing the manner of securing the cutter-blades to the sickle-bar by means of the stay-loops. Fig. 3 is a top view of the cutter-blade, showing the position of the slot that receives the stay-loop.

The nature of my improvement consists, first, in the peculiar shape and manner of constructing the sickle-bar of harvesting-machines; secondly, in the peculiar construction and arrangement of devices by which the cutter-blades are secured to the sickle-bar.

To enable others skilled in the art to make and use my improvement, I will proceed to describe its construction and arrangement.

The bar D, to which the cutter-blades *a* are attached, is constructed of the form and shape of the letter **V**, and at such an angle as will insure to the slot B such a bevel as will securely hold the stay-loop V in position when passed up through the slot B and locked in the blade *a*.

By this peculiar construction of the sickle-bar D the stay-loops V are not only held securely in position, but the sickle-bar is itself very greatly strengthened, and less liable to bend or break in case the cutters become choked or otherwise obstructed.

The bar D is provided with a stay-pin, I, against which the blade *a*¹ rests. The bar D is further provided, at its opposite end, with a drag-screw and nut, C, that secures the blades in position, when placed on the bar D, (see Fig. 1,) by being screwed against the blade *a*² at the end of the bar D. The cutter-blades *a*

a are constructed of any desirable shape or size, and are provided with a beveled slot, B, about their center, for the purpose of admitting and securely holding in position the stay-loop V, that secures the blades *a* to the sickle-bar D.

The stay-loops V are so constructed as to exactly fit into the slot B of the blades *a*, and of such shape as to exactly correspond to and fit over the bar D. (See Fig. 2.) Said stay-loops V may be slightly flared at each end, so as to give them a wedge shape, that will the more securely hold them in position and prevent their being forced up through the slot B of the blades *a* in case the free action of the cutter-blades *a* is in any way obstructed.

After the several parts of my harvester-cutter have been carefully prepared, as above described, the stay-loops V are placed in the slot B of each cutter-blade, passed up and through each slot sufficiently far to admit the sickle-bar D between the stay-loops V and blades *a*, thus effectually securing the cutter-blades *a* to the sickle-bar D by means of the stay-loops V and slot B.

After a sufficient number of blades have been secured to the bar D, as above described, the nut C is drawn against the blade *a*², next to the end of the bar D, thus compactly and substantially securing the whole in position.

Having fully set forth and described my improvement in harvester-cutters, what I claim, and desire to secure by Letters Patent of the United States, is—

1. The sickle-bar D, as shown and described, and for the purpose specified.
2. The stay-loop V, as shown and described, and for the purpose set forth.
3. The beveled slot B, draw-nut C, and stay-pin I, when used in combination with the sickle-bar D, and stay-loop V, as shown and described, and for the purpose specified.

G. L. DU LANEY.
